UNITED STATES PATENT OFFICE.

JOSEPH E. KENNEDY, OF NEW YORK, N. Y., AND LEIGH A. HUNT, OF LAWRENCE,
MISSOURI; SAID HUNT ASSIGNOR TO SAID KENNEDY.

DISINTEGRATING APPARATUS.

Application filed March 26, 1925. Serial No. 18,359.

This invention relates to apparatus for disintegrating material, such as ores, minerals, rock, lime, clinker, and other materials, in wet condition, and it is the object of the 5 invention to provide apparatus of this character which is simple and compact in structure and whereby a product of a uniform degree of fineness is produced.

It is a further object of the invention to 10 provide apparatus of this character including a revoluble drum having means therein operative to disintegrate material through the revolving action of the drum wherein the disintegrated material is delivered to a 15 screening chamber constructed integral with the drum and having a connection with the disintegrating chamber whereby the disintegrated material is delivered thereto through the revolving action of the drum, said screening 20 chamber being arranged with outlet means for delivering the screened material therefrom and to return coarse material to the disintegrating chamber, and said delivery means being adapted to function through 25 the revolving of the drum.

Another object of the invention relates to 30 apparatus of this character wherein the drum is arranged with primary and secondary disintegrating chambers, the drum having a screening chamber constructed integral therewith and intermediate the disintegrating chambers to which disintegrated material is delivered from the primary disintegrating chamber, said screening chamber 35 having connection with the primary disintegrating chamber to return coarse material thereto and connection with the secondary disintegrating chamber to deliver screened material thereto.

A further object of the invention relates 40 to apparatus as above described arranged with primary and secondary disintegrating chambers and a screening chamber wherein the secondary disintegrating chamber is 45 provided with delivery means arranged to screen material delivered from said secondary disintegrating chamber.

Other objects and advantages will herein-after appear.

In the drawings accompanying and forming 50 a part of this specification, there is shown an embodiment of the invention wherein Figure 1 is a longitudinal sectional view taken substantially on the line 1—3 of

Figure 2 looking in the direction of the 55 arrows.

Figure 2 is a cross sectional view taken substantially on the line 2—2 of Figure 1 looking in the direction of the arrows.

Figure 3 is a side elevation of the central 60 portion of the drum to show the arrangement of the screening chamber relative thereto and the connections of said chamber with the primary disintegrating chamber of the drum to receive material therefrom and to 65 said chamber to return coarse material thereto, and also showing the connection of the screening chamber with the secondary disintegrating chamber to deliver screened material to the latter. 70

Figure 4 is an end elevation, looking at 75 the left of Figure 3, of a collecting chamber interposed between the primary and secondary disintegrating chambers, one wall of which constitutes an end wall of the secondary disintegrating chamber and said wall being partly broken away to show the other wall of the collecting chamber and which constitutes an end and screen wall of the primary disintegrating chamber. 80

Figure 5 is a cross sectional view taken 85 substantially centrally through Figure 4 showing the parts in disassembled relation to illustrate the construction and arrangement of the walls of said chamber to arrange a passage therein through which to discharge the material from the screening chamber to the secondary disintegrating chamber.

Figure 6 is a fragmentary view in perspective to show the arrangement of the screening chamber in relation to the drum with a screen separating the chamber into two compartments the one compartment having a connection with the collecting chamber to receive material delivered to said latter 95 chamber from the primary disintegrating chamber, and showing the connection of the other compartment with the secondary disintegrating chamber to deliver screened material thereto. 100

Figure 7 is a detail view in perspective of 105 a deflector arranged between the walls of the collecting chamber shown in Figures 4 and 5 and intermediate the ends of the passage therein to direct the screened material from the screening chamber through an opening in the wall of the collecting chamber into the secondary disintegrating chamber.

Figure 8 is a perspective view, partly broken away, looking at the surface of the wall between the collecting and secondary disintegrating chambers to show the arrangement of said wall with reinforcing ribs for the other wall of the collecting chamber and the arrangement of the passage in the collecting chamber through which to discharge material from the screening chamber to the secondary disintegrating chamber.

Figure 9 is a fragmentary view, in perspective, of a portion of the drum to show the arrangement of the screening chamber relative to the drum with said chamber partly broken away to show the interior structure, and also showing the connection of the screening chamber and the primary disintegrating chamber with the collecting chamber interposed in the drum intermediate the primary and secondary disintegrating chambers.

The embodiment of the invention shown in the drawings comprises a drum D consisting of a cylindrical shell arranged with 25 heads 8, 9 at the opposite ends having axially projecting hollow trunnions 10, 11 whereby the drum is revolvably supported in bearings 12 mounted upon a supporting foundation 13. The trunnions are of relatively large 30 diameter to provide a large bearing surface and have mounted therein annular members 14, 15 to reduce the size of the openings through the drum trunnions and thereby maintain the capacity of the drum, the opening 35 through the reducer 14 constituting the charging opening of the drum and the opening in the reducer 15 the delivery opening. The cylinder is arranged with a wear resisting lining consisting of annular axially arranged sections 16 of suitable material, such 40 as manganese steel, said sections being retained against displacement in the shell by plugs 17 engaging in recessed portions of the lining sections and secured to the shell 45 by bolts as shown. The drum is revolved from a suitable source of power by means of a gear 18 arranged concentric of and fixed to the drum. The material is fed to the drum by means of a hopper 19 fixed to the charging 50 trunnion to revolve with the drum, said hopper having an axial inlet opening 20 and an outlet communicating with a sleeve 20' engaging in the opening in the trunnion reducer with a spirally and angularly arranged partition 21 in said hopper operating 55 through the revolving of the drum to carry material in the hopper from below the axis of the hopper to above the axis and in such latter position direct the material into the 60 sleeve in the opening in the trunnion reducer, said opening having a spiral rib or screw 21' therein to feed the material through the sleeve 20' into the drum.

The drum is separated into axially arranged chambers comprising a primary dis-

integrating chamber A, a collecting chamber B to receive disintegrated material from the primary disintegrating chamber, a secondary disintegrating chamber C, in which to receive and reduce material to a finer degree 70 which material has been subjected to primary disintegrating action in the primary disintegrating chamber, and a secondary collecting chamber E to receive disintegrated material from the secondary disintegrating 75 chamber. The disintegrating chambers A and C have freely moving disintegrating or grinding elements therein, such as steel balls, operative through the revolving of the drum to disintegrate material in said chambers.

The collecting chamber B is arranged in interposed relation to the disintegrating chambers A and C and separated from the chamber C by a transverse partition 22 and from the chamber A by a wall 23 having perforations 24 to provide a screen partition between the primary disintegrating chamber and said collecting chamber through which to deliver disintegrated material from the primary disintegrating chamber A to the collecting chamber B. The openings in this wall 23 have greater length than width and the walls thereof diverge from the side facing the disintegrating chamber A to the opposite side, said openings being arranged in concentric circular rows with the openings of the different rows inclining in opposite directions as shown. By this arrangement of the wall of the openings there is no possibility of the material packing in and clogging the openings. The screen wall 23 consists of segments and the walls 23, 22 of the collecting chamber are secured together by bolts 25 and rivets 26, the walls being maintained in spaced relation by radial ribs 27 arranged preferably integral with the wall or plate 22, said ribs being located so that they will engage the segments of wall 23 at the meeting edges, as clearly shown in Figure 4. These ribs begin at a point outward from the axis of the plate 22 and terminate within the periphery thereof to provide annular passages between the inner and outer ends of said ribs with which the radial 100 passages formed by the ribs communicate. The outer peripheral portion of the segments constituting wall 23 and the plate or wall 22 have laterally extending flanges 28 and 29 which are adapted to meet when the walls are secured together to form the peripheral wall of the collecting chamber B.

The material received in the collecting chamber B is delivered to an annular screening chamber (designated in a general way at F) fixed to the drum in concentric relation thereto and to revolve therewith, said chamber extending around a portion of the drum in which the disintegrating chamber A is arranged and that portion of the drum in which the collecting chamber B is ar-

ranged. The screening chamber is separated by an annular screen partition 34 into concentric compartments G and H. The compartment G is connected to the collecting chamber B to receive material on the screen 34 through openings 35 arranged in the flanges 28, 29 of walls 23 and 22, and that portion of the drum containing the collecting chamber, there being four of these openings in the present instance equidistantly spaced apart around the periphery of the drum. The material flows through said openings 35 from the collecting chamber onto the screen partition 34 in the screening chamber when said openings are below the axis of the drum. The outer wall of the screening chamber is constructed of semi-circular plates having the ends flanged laterally whereby they are secured together by rivets or bolts, as shown at 30, and end or side walls 31 consisting of semi-circular plates to engage within the outer wall and flanged laterally whereby they are secured to the wall by rivets or bolts, as shown at 32, and reinforced by angle iron 33, the screen being secured to the drum by angle iron 33' riveted or bolted to the side walls 31 and the drum.

The material received in the compartment G on the screen 34 passes through the meshes of the screen into the compartment H and any material which is too coarse to pass through the meshes of the screen is returned to the primary disintegrating chamber A for regrinding. For this purpose the compartment G of the screening chamber is arranged with openings 36, there being two of these outlet openings arranged in the wall of the drum and at the end of the screening chamber opposite the inlet openings 35. The material through the action of centrifugal force as the drum is revolved will tend to be thrown outward against the screen wall 34 and the material is directed toward the outlet openings 36 by a spirally arranged rib 37 in the form of angle iron secured to the screen wall within the chamber G. The material is directed by said rib to vanes 38, which may be in the nature of pockets, which will pick up the material from below the axis of the drum and lift the material toward the axis of the drum, and as said vanes approach the axis of the drum they are so constructed that they will direct or deflect the material through the openings 36, and as the material passes through said openings they will engage deflectors 38' within the primary disintegrating chamber, said deflectors 38' also serving as a means to prevent material from the primary disintegrating chamber entering the screening chamber through the openings 36.

The screened material which is passed through the screen 34 to the outer compartment H of the screening chamber F is de-

livered into the secondary disintegrating chamber C to be reduced to a finer degree by the action of disintegrating elements in said chamber, in the form of steel balls or the like. For this purpose there is arranged in the collecting chamber B a passage-way 39 having inlets 40 arranged diametrically opposite through the flanges 28, 29 of the wall 23, 22 of the collecting chamber, said passage having an outlet 41 arranged axially in the wall 22 and leading into the secondary disintegrating chamber. The passage 39 is formed by parallel and spaced apart ribs 42 extending radially outward from the outlet opening 41 to the periphery of the plate 22. To direct material through the outlet opening 41 a deflector is arranged in the passage intermediate the ends thereof, said deflector comprising a disk 43 (Figures 5 and 7) secured in position by the bolts 25 which serve to connect the walls of the collecting chamber, and said disk being arranged with opposite peripheral walls 44 to constitute a continuation of the passage walls 32 and having a portion 45 of V-shape in cross section the apex of the opposite inclined walls of which are arranged axially of the opening 41 and have semi-circular portions 46 extending laterally from the parallel walls 44 to engage a corresponding seat 47 formed about the outlet opening 41 and to engage the inner ends of the radial reinforcing ribs 27 on the plate or wall 22 to prevent material from the collecting chamber B being discharged into the secondary disintegrating chamber C. The inlets 40 of the passage 39 are connected to the compartment H of the screening chamber by means of tubular members 48 of the same cross sectional shape as the passage extending through the compartment G of the screening chamber. Material from the compartment H of the screening chamber is delivered to the passage 39 through the tubular member 48 spaced apart approximately ninety degrees around the periphery of the drum whereby as said outlets 48 from the compartment H are below the axis of rotation of the drum material from the compartment H will enter said members and is lifted upward with the movement of the drum and as they are positioned above the axis of rotation of the drum the material will pass through said connecting members into passageway 39 and through the latter into the secondary disintegrating chamber C. To cause the material from the compartment H to enter the passage 39 deflectors are arranged in compartment H, which are in the nature of partitions 49 extending from the outer wall of the compartment to the screen partition 34 and spirally arranged to extend from the side wall 31 at the side of the screen chambers opposite said openings 48 and in a direction toward said openings, the portion of the

- screen partitions 34 adjacent the outlets between said deflectors and the side wall 31 being preferably arranged with an unperforated material to prevent re-entering of the material through the screen partition into the compartment G from compartment H.
- The disintegrated material from the secondary disintegrating chamber C is delivered through a transverse screen partition 10 49' into the chamber E. This partition has openings therethrough of a structure and arrangement similar to the openings 24 through the partition 23 and has an opening centrally thereof and axially of the drum leading to the delivery opening through the trunnion reducer 15, the wall of said opening flaring outward from the drum and being of less diameter than the reducer opening to provide an annular space 50 between 15 said partition and the reducer opening to constitute the outlet for the chamber E. The partition 49' is connected to and carried by the drum head 9 and trunnion reducer by bolts 51 and maintained in spaced 20 relation to said head by spacers 52, said spacers being arranged as scoops or buckets to pick up the material in the chamber E from below the axis of the drum and lift it through the revolving of the drum to above 25 the axis of the drum and direct it to the space between the partition 49 and the reducer 15 to deliver the material therethrough.
- The material is delivered from the chamber E through the trunnion reducer 15 onto a cylindrical screen 53 connected to said trunnion reducer to extend co-axially thereof, the material passing through said screen being collected in a hopper arranged below 30 the screen from which it is delivered to a suitable receiver, while any coarse particles of material are delivered from the outer end of the screen into a suitable receiver therefor.
- A tubular member 54 is connected to the 35 trunnion reducer 15 as by bolts passing through perforated lugs extending laterally from said member and inwardly from said reducer, as shown at 55, said member being of a diameter less than the internal diameter 40 of the trunnion reducer and substantially of the same diameter as the flaring wall of the central opening of the partition 49 and constituting an extension of said wall to extend substantially for the full length of the screen 53. This tubular member 54 is for the purpose of feeding the grinding elements to the 45 secondary disintegrating chamber C, and to facilitate the feeding of said grinding elements there is arranged on the inner peripheral wall a spiral rib or screw 56 which operates to propel the grinding elements through said member by the revolving of the drum. The material to be disintegrated together with liquid, such as water, is delivered to the primary disintegrating chamber 50
- 55

A through the charging opening leading to said chamber.

While there has been described and illustrated one embodiment of the invention, it is obvious that various changes and modifications may be made in the form and structure of the apparatus, and that portions of the invention may be used without others, and come within the scope of the invention. 70

Having thus described our invention we 75 claim:

1. In disintegrating apparatus, a revolvable drum having a transverse screen partition to arrange the drum with a disintegrating chamber having a charging opening and a collecting chamber to receive disintegrated material through the screen partition from the disintegrating chamber; a passage extending transversely of the collecting chamber having an outlet axially of the 80 drum; a chamber concentric to and revolvable with the drum having a screen partition separating the chamber into a pair of concentric compartments; means to connect the compartment at inner side of the screen in 85 said chamber with the collecting chamber arranged to deliver material from the collecting chamber to said compartment during the revolving of the drum; outlets from said compartment through the peripheral wall 90 and intermediate the ends of the disintegrating chamber to return coarse material from said compartment to the disintegrating chamber during the revolving of the drum; and outlets leading from the outer compartment of the screen chamber connected to the 95 transverse passage in the collecting chamber through which to discharge screened material from said compartment during the revolving of the drum, said passage being arranged with a deflector to direct material 100 discharged thereto through the axial outlet thereof.

2. In disintegrating apparatus, a revolvable drum having a charging opening and a delivery opening, said drum being separated into a primary disintegrating chamber with which the charging opening communicates and a second disintegrating chamber with which the delivery opening communicates; 110 and a screening chamber concentric and intermediate the ends of and revolvable with the drum having a connection at one end with the primary disintegrating chamber to receive disintegrated material therefrom during the revolving of the drum; and outlet means from said screen chamber leading through the peripheral wall of and intermediate the ends of the primary disintegrating chamber to return coarse material 115 to said chamber and leading axially to the secondary disintegrating chamber to deliver screened material to said latter chamber. 120

3. In disintegrating apparatus, a revolvable drum having a charging opening; a 125

- transverse screen partition in said drum separating the drum into a disintegrating chamber with which the charging opening communicates and a collecting chamber to receive material through the screen partition; a chamber concentric and intermediate the ends of and revoluble with the drum; a screen partition separating said chamber into a pair of compartments; outlet means from the collecting chamber connected to one end of the compartment at one side of the screen partition; outlets leading from the opposite end of said compartment through the peripheral wall of the disintegrating chamber and at a point intermediate the ends thereof to return coarse material from said compartment to the disintegrating chamber; means in said chamber to direct material therein toward the outlets during the revolving of the drum; outlets from the other compartment of the screening chamber to deliver screened material therefrom; and means in said chamber to direct material therein toward the outlets during the revolving of the drum.
4. In disintegrating apparatus, a revoluble drum having a charging opening and a delivery opening, said drum being separated into a primary disintegrating chamber with which the charging opening communicates and a secondary disintegrating chamber with which the delivery opening communicates; a screening chamber concentric of and revoluble with the drum having a connection with the primary disintegrating chamber to receive disintegrated material therefrom the end thereof opposite to the charging end during the revolving of the drum, and outlet means from the screening chamber leading through the peripheral wall of and intermediate the ends of the primary disintegrating chamber and axially to the end of the secondary disintegrating chamber opposite to the discharge outlet to return coarse material to the primary disintegrating chamber and screened material to the secondary disintegrating chamber; and means in the drum to receive disintegrated material from the secondary disintegrating chamber and deliver the same through the delivery opening of the drum during the revolving thereof.
5. In disintegrating apparatus, a revoluble drum having a charging opening and a delivery opening, said drum being arranged with a primary disintegrating chamber with which the charging opening communicates and a secondary disintegrating chamber; a chamber to receive and collect disintegrated material from the primary disintegrating chamber; a chamber concentric to and revoluble with the drum having a screen partition therein to separate the chamber into a pair of compartments; outlet means from the collecting chamber leading to the inlets at one end of the compartment at one side of the screen partition in the screening chamber; outlets from the opposite end of said compartment connected with the primary disintegrating chamber through the peripheral wall and intermediate the ends thereof; means operative during the revolving of the drum to direct material through said chamber from the inlets to the outlets to return coarse material through said chamber to the primary disintegrating chamber; and outlet means from the other compartment of the screening chamber having a connection extending transversely through the collecting chamber and having outlets arranged axially of the secondary disintegrating chamber to deliver screened material to said latter chamber, said outlet means being arranged to receive material from below the center of gravity of the drum, lift the matter above the center of gravity and deliver the same upon the material in the respective disintegrating chambers.
6. In disintegrating apparatus, a revoluble drum having a charging opening and a delivery opening, said drum being arranged with a primary disintegrating chamber with which the charging opening communicates and a secondary disintegrating chamber; a collecting chamber in the drum interposed between said primary and secondary disintegrating chambers having a screen partition between said chamber and the primary disintegrating chamber through which to receive disintegrated material from the primary disintegrating chamber; a screening chamber concentric and intermediate the ends of the drum having inlet means to the one end thereof from the collecting chamber; outlet means from the opposite end of said screening chamber connected with the primary disintegrating chamber through the peripheral wall and intermediate the ends thereof to return coarse material to the primary disintegrating chamber; a passageway extending through the collecting chamber having inlets through the peripheral wall of said chamber leading from the end of the screening chamber opposite to the outlet means connected to the primary disintegrating chamber and an outlet axially of the secondary disintegrating chamber; and outlet means from the screening chamber connected with the inlets of said passageway to deliver screened material from the screening chamber to the secondary disintegrating chamber, said outlet means being arranged and operative during the revolving of the drum to carry the material in said chamber from below the center of gravity, lift and deliver the material into the respective disintegrating chambers above the center of gravity.
7. In disintegrating apparatus, a revoluble drum having charging and delivery open-

- 6
- ings at opposite ends and arranged with a primary disintegrated chamber with which the charging opening communicates and a secondary disintegrating chamber; a collecting chamber in the drum to receive disintegrated material from the primary disintegrated chamber; a screening chamber arranged concentric of and revoluble with the drum to receive material from the collecting chamber and having a connection with the primary disintegrating chamber through the peripheral wall thereof to return coarse material thereto and an axial connection with the secondary disintegrating chamber to deliver screened material thereto; a chamber in the drum outlet at the end of the secondary disintegrating chamber to receive disintegrated material from said chamber; means in said receiving chamber operative during the revolving of the drum to deliver material therefrom through the delivery opening of the drum; and means arranged axially of the delivery opening arranged for the feeding of grinding elements into the secondary disintegrating chamber.
8. In disintegrating apparatus, a revoluble drum having charging and delivery openings and arranged with a primary disintegrating chamber with which the charging opening communicates and a secondary disintegrating chamber; a collecting chamber in the drum to receive disintegrated material from the primary disintegrating chamber; a screening chamber arranged concentric of the drum to receive material from the collecting chamber and having a connection with the primary disintegrating chamber to return coarse material thereto and a connection with the secondary disintegrating chamber to deliver screened material thereto; a second collecting chamber in the drum at the outer end of the secondary disintegrating chamber, said chambers having a screen partition between the same through which disintegrated material is delivered from the secondary disintegrating chamber to said collecting chamber; lifters in said collecting chamber operable during the revolving of the drum to deliver material from said chamber through the delivery opening of the drum; a screen arranged axially of the delivery opening of the drum to screen material delivered from the secondary collecting chamber through the delivery opening and means arranged axially of the screen at the delivery opening and leading to the secondary disintegrating chamber for feeding grinding elements to said chamber during the revolving of the drum.
9. In disintegrating apparatus, a revoluble drum arranged with a primary disintegrating chamber having a charging opening in communication therewith and a secondary disintegrating chamber; a collecting chamber in the drum to receive disintegrated material from the primary disintegrating chamber; a screening chamber arranged concentric of and revoluble with the drum to receive material from the collecting chamber and having a connection with the primary disintegrating chamber to return coarse material thereto through the peripheral wall and intermediate the ends thereof and a connection with the secondary disintegrating chamber to deliver screened material thereto axially at one end; a collecting chamber in the drum at the outer end of the secondary disintegrating chamber, said chambers having a screen partition between the same through which disintegrated material is delivered from the secondary disintegrating chamber to said collecting chamber; lifters in said collecting chamber operable during the revolving of the drum to deliver material from said chamber; and a screen arranged axially of the drum to receive and screen material delivered from the collecting chamber connected to the secondary disintegrating chamber.
10. In disintegrating apparatus, a revoluble drum arranged with a primary disintegrating chamber having a charging opening and a secondary disintegrating chamber; a collecting chamber in the drum to receive disintegrated material from the primary disintegrating chamber; a screening chamber arranged concentric of and revoluble with the drum to receive material from the collecting chamber and having a connection with the primary disintegrating chamber to return coarse material thereto and a connection with the secondary disintegrating chamber to deliver screening material thereto; a chamber in the drum at the end of the secondary disintegrating chamber to receive disintegrated material from said disintegrating chamber; means in said receiving chamber operative during the revolving of the drum to deliver material therefrom; and means arranged axially of the delivery opening of said receiving chamber and leading to the secondary disintegrating chamber arranged for feeding disintegrating elements to the secondary disintegrating chamber.

JOSEPH E. KENNEDY.
LEIGH A. HUNT.
